UNITED STATES PATENT OFFICE.

HARRY URLASS, OF LANCASTER, PENNSYLVANIA.

CLAMPING DEVICE FOR MOLDING FLASKS.

Application filed December 29, 1921. Serial No. 525,602.

To all whom it may concern:

Be it known that I, HARRY URLASS, a citizen of the United States, residing at Lancaster, in the county of Lancaster and State 5 of Pennsylvania, have invented certain new and useful Improvements in Clamping Devices for Molding Flasks, of which the following is a specification.

The present invention relates to improvements 10 in clamping devices for molding flasks, the object in view being to provide a simple article capable of effectively and firmly drawing together the parts of the flask and holding them in such position during 15 the ramming operation but permitting ready release of the mold sections when stripping is to be performed.

More particularly, it may be stated that the primary object of my invention is to 20 provide a construction of lock which produces a double drawing or clamping action upon the flask sections by such an arrangement of a cam and clamping element that in the locking operation one section of the flask is drawn to the other in one direction, while the latter section is correspondingly drawn to the first section in a direction at right angles to the first mentioned direction.

It is further my object to provide a locking 30 device of the character mentioned which combines with the clamping feature means for insuring accurate alignment of the flask sections.

These and such other objects as may hereinafter appear are attained by the novel construction, combination and arrangement 35 of parts to be hereinafter specifically described and claimed.

Reference will now be had to the accompanying 40 drawings forming a part of this specification wherein:

Figure 1 is a perspective view of a flask having my invention applied thereto.

Figure 2 is a detail view of the lock showing 45 the clamping section of the locking device in plan and in mold locking position.

Figure 3 is a view looking at the device at right angles to that of Figure 2 and showing in plan the cam section of the locking 50 device.

Figure 4 is a sectional view taken about on the plane indicated by the line 4-4 of Figure 2.

Figure 5 is a composite view of the two 55 parts of the device embodying the aligning

interlock means forming a feature of this article.

Referring to the drawing and specifically describing the invention, it will be understood that the clamping device forming the subject-matter hereof is designed especially for molding flasks, and the embodiment of the drawing shows its application to a conventional two-part flask, one part being designated A and the other B, these parts 60 being pivotally secured together at the corner C. The meeting end of the section B where the clamping device is attached is rabbeted as indicated at D so as to form a shoulder E against which the end of section 65 A is received.

Bearing this construction in mind, the locking device comprises at least two main parts, that which I will term for purposes of convenience the cam part or section 1, and the clamping part or section 2. In reality the latter part comprises a base plate 3 which is secured permanently to the flask section by means of the screws 4; the plate being provided with an apertured boss 5 upon 70 which is pivotally mounted the clamping member 6, said member being suitably recessed to receive the boss and being secured to the plate by the pivot 7. The boss 5 forms a bearing for the clamping member 75 and relieves the pivot of much of the stresses imparted by the clamping action. The locking member 6, as best seen in Figure 2, is provided at one end with a wing 8 and at its opposite end with a corresponding wing 80 9, so that it is manipulated very much like a wing nut. The offstanding end of the clamping member, beneath the juncture of the wing 9 with the body, is formed with a clamping finger or hook 10 which coacts 95 with the cam section 1 of the locking member to produce the peculiar clamping effect which will be later described.

Referring to the cam section 1, it will be observed by reference to Figure 4 that a shoulder 11 is formed at an intermediate point so as to engage with the edge of the flask section A to which the cam section is secured by means of suitable screws 12. At the free end of this member is formed a lateral flange 13 which has an edge cam face 14 and a second cam or side cam face 15, the latter being formed by a thickening of the metal at the upper part as shown at 15 105 in Figure 3. In the cooperation of the 110

clamping member 6 with the cam section 1, the hook 10 engages about this flange and as the member 6 is rotated the shank of the hook rides upon the edge cam 14 while the 5 end of the hook rides on the side cam face 15. This cooperation produces a double camming action in that the cam 15 draws the section B tightly against the meeting end of the section A while the cam 14 draws 10 the side of the meeting end of section A against the shoulder E, referred to above, of section B. A very tight clamp is thus produced by a simple rotation of the revoluble member 6. A very slight tap upon the wing 15 9 will cause the member 6 to release the sections of the flask when it is desired to strip.

A further feature which is not infrequently accomplished by aligning means separate and distinct from flask locks, resides 20 in the formation of the parts of my device with an aligning interlock that produces the aligning at the time the locking device is brought into play. In other words, as shown in Figure 5, the part 1 at its edge 25 is provided with a recess or socket 17 to receive a projecting lug or tongue 18 on the plate 3, so that as the flask is closed this tapered tongue will slide into a correspondingly formed seat to automatically 30 align the flask sections accurately as desired at the same time that the locking of the flask sections together takes place.

A very simple and effective article of manufacture is thus provided by this device, and I desire it to be particularly understood that I do not confine myself to the application of the locking means to flasks as it may be employed elsewhere with equal effectiveness. Furthermore, slight 40 changes in the details of construction may be made without departing from the spirit of the invention and within the scope of the claims hereto appended.

Having thus described my invention, 45 what I claim as new and desire to secure by Letters Patent is:

1. A clamping device for molding flasks comprising a section having a flange provided with double cam faces, and a clamping member having means engageable with each 50 of the cam faces to produce a clamping action in two directions.

2. A clamping device for molding flasks comprising a section having at one end thereof a laterally projecting flange formed with edge and side cam faces, and a clamping member pivotally mounted and formed

to engage about the flange so as to ride upon each of the cam faces aforesaid.

3. A clamping device for molding flasks 60 comprising a member secured to one of the flask sections and provided at its end with cam faces arranged at angles to each other, and a clamping member pivotally secured to the other flask section and having a 65 clamping finger formed to engage the cam faces aforesaid to thereby produce a clamping action of the mold sections in two directions.

4. A clamping device for molding flasks 70 or the like comprising a cam member mounted upon one of the flask sections, and a clamping member mounted on the other of said mold sections engageable with the cam member, and aligning means on said 75 members adapted to interlock in the closing of the flask sections.

5. A clamping device for molding flasks or the like comprising a cam member attached to one of the sections of the flask, 80 and a clamping member attached to the other section of the flask, one of said members being provided with a recess and the other with a lug projection adapted to engage in the said recess to align the flask sections as an incident to the clamping action by the clamping member.

6. A clamping device for molding flasks or the like comprising a member attached to one of the flask sections having a cam 90 surface and a socket, and a clamping member attached to the other flask section and comprising an attaching plate having an aligning lug adapted to be received in the socket aforesaid and a clamping member mounted upon said plate engageable with said cam face to thereby clamp the flask sections together and simultaneously align said sections.

7. A clamping device for molding flasks 100 or the like comprising a member having a double cam formed thereon and attached to one section of the mold flask, and a clamping member attached to the other section of the mold flask and including an attaching plate and a rotatable clamping member formed with diametrically opposed wing elements for manipulating the clamping member and having a clamping finger projecting therefrom engageable with the two 110 cam faces aforesaid.

In testimony whereof I affix my signature,

HARRY URLASS.
